UNITED STATES PATENT OFFICE.

DAVID M. KEY, OF DALLAS, TEXAS.

COTTON-GATHERING MACHINE.

Application filed January 2, 1925. Serial No. 86.

This invention relates to new and useful improvements in cotton gathering machines.

The object of the invention is to provide a machine in the form of a trailer which 5 may be attached to a wagon or truck and drawn along the rows to gather the cotton and unopened bolls.

Another object of the invention is to provide a machine of the character described 10 having teeth for removing and gathering the cotton and bolls and means for elevating and delivering the same to the body of the wagon or truck.

A further object is to provide means for 15 cracking the unopened bolls, whereby a portion of the hulls and trash will drop off the elevator, thus requiring less cleaning.

A still further object is to provide a self 20 driving machine which merely requires attachment to a wagon or truck to give traction and operate.

A construction designed to carry out the invention will be herein after described together with other features of the invention.

The invention will be more readily understood from a reading of the following specification and by reference to the accompanying drawings, in which an example of the 25 invention is shown, and wherein:

30 Fig. 1 is a plan view of a cotton gathering machine constructed in accordance with my invention.

Fig. 2 is a side elevation of the same partly in section,

35 Fig. 3 is a rear elevation, and

Fig. 4 is a detail of the driving connections.

In the drawings the numeral 10 designates 40 a supporting axle which is made fast in ground wheels 11. The axle bears upon longitudinal reach bars or beams 12 and is rotatably confined by bearing blocks 13 bolted on the rear ends of the beams. The beams are long enough to reach under a body

45 A of a wagon and bolt to the rear axle B thereof.

The beams are spaced apart as is shown in Figs. 1 and 3 and each has the lower end of a standard 14 seated therein. The trough 50 for an elevator or inclined conveyor comprises sideboards 15 connected by transverse bottom bars 16 and top cross brackets 17. The side boards are fastened to the upper ends of the standards. Right angular metal brackets 18, secured to the bar 16 55 at the bottom of the conveyor have bearing

eyes receiving a shaft 19 carried by the beams. These brackets support the lower end of the conveyor and are located at each end of a large drum 20 mounted on the shaft 60 between the side boards.

At the upper ends of the side boards is journaled a transverse shaft 21 on which is mounted a small drum, 22. A conveyor belt 23 has its ends supported in the drums. 65 This belt which may be of suitable material has transverse strips 24 secured on its face. The conveyor overhangs the body A of the wagon for guiding the discharge into the body. The belt 23 and drums 20 and 22 70 constitute the conveyor.

Plates 26 are secured to the inner sides of the beams at the lower ends of the conveyor. In these plates are supported in concentric relation to the shaft 19 and drum 75 20, an upper transverse shaft 27, an intermediate transverse shaft 28 and a lower transverse shaft 29. On the shaft 27 is mounted a drum 30; while drums 31 and 32 respectively, are mounted on the other shafts. 80 These drums are made of wooden cylinders or suitable material and revolve in close proximity to the belt, there being just enough clearance for the strips or slats.

At the lower ends of the plates is fastened 85 a transverse bar 33 and forwardly curved tines or fingers 34 have their rear ends fastened in said bar. These tines are suitably spaced apart to support the bolls and permit the stems and leaves to pass there- 90 through. The tines underlie the drum 20 and engage the cotton plants to remove the cotton and bolls therefrom. Stirrups 35 depend from the plates and have journaled 95 therein a beater shaft 36. Radial fingers or prongs 37 carried by the shaft move between or just under the tines for removing vines or other trash.

For driving the various parts a large sprocket 38 is fastened on the axle 10 and 100 drives a sprocket chain 39 having its forward end passing around and driving a smaller sprocket 40 fastened on the shaft 19, whereby the drum 20 and the conveyor are driven. The upper run of the chain 105 passes under and drives a sprocket 41 fastened on the shaft 28; while the lower run of the chain passes under and drives a sprocket 42 fastened on the beater shaft 36. On the opposite side of the drums a pair 110 of sprockets 43 and 44, respectively are fastened on the shaft 28. The sprocket 43

drives an endless chain 45 which drives a sprocket 46 on the shaft 27; while the sprocket 44 drives an endless chain 47 which drives a sprocket 48 on the shaft 29. The 5 wheels 11 being revolved forwardly revolve the drum 20 in a clockwise direction by the chain 39, but the sprocket 41 is driven in a counter clockwise direction and the sprocket 42 in a clockwise direction. This revolves 10 the beater so that it pulls vines down between the tines and forwardly. The shaft 28 and drum 31 are driven counter clockwise as are likewise the chains 45 and 47 and the drums 30 and 32.

15 It is to be understood that various changes and modifications can be made in the driving connections and the arrangement of the different parts as described and illustrated is subject to variation, all within the scope 20 of the appended claims.

In using the machine the beams 12 are attached to rear axle B of a wagon or truck so that the inclined conveyor belt 23 will overhang the body A and discharge thereunto. As the machine is drawn along the 25 rows of cotton plants by the wagon the drums 20, 22, 30, 31 and 32 will be put in motion. The tines 34 will engage the cotton plants and pull the cotton locks and unopened bolls therefrom and as these work 30 rearwardly on the tines they will be taken up by the belt 23 and carried around the drum 20. When the cotton and unopened bolls are elevated they are brought into contact with the drums 30, 31 and 32, whereby 35 the unopened bolls are crushed. The conveyor belt 23 passing between the drum 20 and the crushing or breaking drums 30, 31 and 32 will carry the locks and unopened bolls therebetween. The bolls are thus 40 crushed or broken on the slatted surface of the belt by the drums 30, 31 and 32, the belt being supported by and stretched over the large drum at this point. The large 45 drum 20 thus has the dual function of supporting and driving the conveyor belt and also acting as an anvil coacting with the small drums in crushing or breaking the bolls. The drums 20, 30, 31 and 32 thus 50 constitute boll crushing or breaking means. The conveyor belt merely acts to carry the bolls between the drums and has no crushing or breaking function. Considerable of the 55 trash will fall out at this point, but the cotton will be carried by the strips 24. The belt will carry the cotton up the conveyor and discharge into the body. This method of gathering is efficient and rapid. While 60 more trash and leaves will be gathered than by the hand method of picking, such can be removed by a suitable cleaner.

What I claim, is:

1. In a gathering machine, the combination of ground wheels, a support carried by 65 the ground wheels and adapted to be attach-

ed to the rear of a vehicle, gathering means carried by the support, a conveyor having a driving drum mounted on the support to discharge into the vehicle and receiving its load from the gathering means, and boll 70 crushing means co-acting with the conveyor driving drum.

2. In a gathering machine, the combination of ground wheels, a support carried by 75 the ground wheels and adapted to be attached to the rear of a vehicle, gathering means carried by the support, a conveyor having a driving drum mounted on the support to discharge into the vehicle and receiving its load from the gathering means, a plurality 80 of boll crushing drums co-acting with the conveyor driving drum, and means for transmitting motion from the ground wheels to the conveyor and drums.

3. In a gathering machine, the combination of ground wheels, a support carried by 85 the ground wheels and adapted to be attached to the rear of a vehicle, gathering means carried by the support in advance of the ground wheels, a large conveyor drum adjacent the gathering means, a smaller conveyor drum for overhanging the vehicle, a conveyor belt having its ends supported on 90 said drums, boll crushing means co-acting with the large conveyor drum and the lower 95 end of the conveyor belt, and means for transmitting motion from the ground wheels to the large drum and the boll crushing means.

4. In a gathering machine, the combination of ground wheels, a support carried by 100 the ground wheels and adapted to be attached to the rear of a vehicle, gathering means carried by the support in advance of the ground wheels, a large conveyor drum adjacent the gathering means, a smaller conveyor drum for overhanging the vehicle, a conveyor belt having its ends supported on 105 said drums, a plurality of boll crushing drums mounted contiguous to the large conveyor drum and the lower end of the conveyor belt, and means for transmitting motion to the large drum and the boll crushing drums.

5. In a gathering machine, the combination of ground wheels, a support carried by 110 the ground wheels and adapted to be attached to the rear of a vehicle, gathering means carried by the support in advance of the ground wheels, a large conveyor drum adjacent the gathering means, a smaller conveyor drum for overhanging the vehicle, a conveyor belt having its ends supported on 115 said drums, a plurality of boll crushing drums mounted concentric to the large conveyor drum, and means for transmitting motion to the large drum and the boll crushing drums.

6. In a gathering machine, the combination of ground wheels, a support carried by 120

the ground wheels and adapted to be attached to the rear of a vehicle, an inclined conveyor mounted on the support for discharging into the vehicle, a plurality of tines 5 under the lower end of the conveyor, boll crushing means in rear of the tines and contiguous to the lower end of the conveyor, a revolving cleaning device contiguous to the tines, and means for transmitting motion 10 from the ground wheels to the conveyor, boll crushing means and cleaning device.

7. In a gathering machine, the combination of ground wheels, a pair of beams carried by their rear ends by the ground wheels 15 and their front ends being adapted to be attached to the rear of a vehicle, an inclined conveyor carried by the beams and including a pair of drums supporting an endless belt, tines mounted under the lower 20 end of the belt contiguous to the lower drum, a plurality of boll crushing drums mounted contiguous to the lower drum of the conveyor, means for driving conveyor belt in a clockwise direction, and means for driving 25 the boll breaking drums in a counter clockwise direction.

8. In a gathering machine, the combination of ground wheels, a pair of beams carried by their rear ends by the ground wheels 30 and their front ends being adapted to be attached to the rear of a vehicle, an inclined conveyor carried by the beams and including a pair of drums supporting an endless belt, tines mounted under the lower end of

the belt contiguous to the lower drum, supports carried by the beams, a plurality of drums mounted in the supports concentrically to the lower drum of the conveyor, means for driving the lower conveyor drum in a clockwise direction, and means for driving 40 the boll breaking drums in a counter clockwise direction.

9. In a gathering machine, the combination of a pair of ground wheels, an axle carried by the wheels, a pair of longitudinal 45 beams having their rear ends supported on the axle and their forward ends adapted for attachment to the rear of a vehicle, standards carried by the beams, inclined conveyor side boards supported on the standards, a small 50 drum at the upper ends of the side boards, a large drum mounted between the beams at the lower ends of the boards, an endless conveyor belt supported on the large and small drums between the side boards, supports 55 carried by the beams, a plurality of boll breaking drums, journaled in the supports contiguous to the large drum, a transverse bar carried by the supports under the large drum and in proximity to lowest boll breaking 60 drum, curved tines directed forwardly from the bar, means for driving the large drum in a clockwise direction, and means for driving the boll breaking drums in a counter 65 clockwise direction.

In testimony whereof I affix my signature.

DAVID M. KEY.
